(57) CLAIM

The ornamental design for package as an accessory for gameboards, as shown and described.

DESCRIPTION

FIG. 1 is a perspective view of the design of the package in an assembled condition;

FIG. 2 is a first side view of the design of the package of FIG. 1 in the assembled condition;

FIG. 3 is a second side view of the design of the package of FIG. 1 in the assembled condition;

FIG. 4 is a plan view of a bottom surface of the package of FIG. 1 in the assembled condition;

FIG. 5 is a plan view of the top surface of the package of FIG. 1 in the assembled condition;

FIG. 6 is a third side view of the design of the package of FIG. 1 in the assembled condition;

FIG. 7 is a fourth side view of the design of the package of FIG. 1 in the assembled condition;

FIG. 8 is a perspective view of the package of FIG. 1 in a disassembled condition; and,

FIG. 9 is a partial perspective view of the top surface of the package of FIG. 1 in the disassembled condition.

The broken lines depict unclaimed environmental subject matter.
